UNITED STATES PATENT OFFICE

147,736

DESIGN FOR A PIN-ON PURSE OR SIMILAR ARTICLE

Evelyn B. Steinberg and Dorris M. Scott,
Los Angeles, Calif.

Application March 6, 1946, Serial No. 127,140

Term of patent 3½ years

(Cl. D87—3)

To all whom it may concern:

Be it known that we, Evelyn B. Steinberg and Dorris M. Scott, both citizens of the United States, residing at Los Angeles, in the county of Los Angeles and State of California, have invented a new, original, and ornamental Design for Pin-on Purse or Similar Article, of which the following is a specification, reference being had to the accompanying drawing, forming part thereof.

Fig. 1, is a front elevational view of a pin-on purse or similar article showing our new design.

Fig. 2 is a side perspective view of the same as viewed from the right side.

Fig. 3 is a front perspective view, on a reduced scale, of the purse or similar article, in an open position, and slightly tilted to disclose the coin receiving opening.

Fig. 4 is a view similar to Fig. 2, but viewed from the left side of the purse or similar article.

We claim:

The ornamental design for a pin-on purse or similar article, as shown.

EVELYN B. STEINBERG.
DORRIS M. SCOTT.
